UNITED STATES PATENT OFFICE

114,147

DESIGN FOR A STORAGE BATTERY CASE

Robert M. Critchfield, Anderson, and Donald B. Roberts, Muncie, Ind., assignors to General Motors Corporation, Detroit, Mich., a corporation of Delaware

Application January 31, 1938, Serial No. 74,756

Term of patent 7 years

To all whom it may concern:

Be it known that we, Robert M. Critchfield and Donald B. Roberts, citizens of the United States, residing at Anderson, in the county of Madison and State of Indiana, and Muncie, county of Delaware and State of Indiana, respectively, have invented a new, original, and ornamental Design for Storage Battery Case, of which the following is a specification, reference being had to the accompanying drawing, forming a part thereof.

In the drawing:

Fig. 1 is a perspective view showing the front side and one end of storage battery case.

Fig. 2 is a perspective view showing the back side and the other end of the battery case.

We claim:

The ornamental design for a storage battery case, substantially as shown.

ROBERT M. CRITCHFIELD.
DONALD B. ROBERTS.
